UNITED STATES PATENT OFFICE

ROY C. CONN, OF CLARKSBURG, WEST VIRGINIA, ASSIGNOR TO PITTSBURGH PLATE GLASS COMPANY, A CORPORATION OF PENNSYLVANIA

APPARATUS FOR MAKING SHEET GLASS

Application filed May 27, 1930. Serial No. 456,256.

The invention relates to apparatus for making sheet glass applicable where a continuous sheet is drawn from an open pool or bath, and involves an improvement on the 5 Slingluff Patent No. 1,549,513 of August 11, 1925. I have found in the use of the Slingluff edge holder that the sheet draws somewhat thin at a point three or four inches in from its edge as indicated at *a* in Fig. 4, 10 which shows a horizontal section of the marginal portion of the sheet. This thinning of the sheet tends to increase breakage, and requires that a wider margin of the edge shall be trimmed off than would otherwise be the 15 case. The present invention is designed to remedy this condition, and involves a modification of the Slingluff edge holder. One embodiment of the invention is illustrated in the accompanying drawings, wherein:

20 Figure 1 is a vertical section through the apparatus. Figs. 2 and 3 are details of the edge holding device, Fig. 2 being a plan view and Fig. 3 being a section on the line III-III of Fig. 2. And Fig. 4 is an enlarged horizontal section through the edge of 25 a sheet produced on the Slingluff machine not employing the improvement to which the present invention relates.

Referring to the drawings, 1 is a drawing 30 tank connected to the end of a suitable melting tank; 2 is the lower end of the casing of the Fourcault drawing apparatus, such apparatus comprising a series of pairs of rolls driven from a series of pairs of gears 3 and 35 serving to draw the glass upward through the casing where it is annealed; 4 is a glass sheet which is being drawn from the glass bath in the tank 1; 5, 5 are the edge holding devices in the form of metal bowls carried by the arms 6, 6; 7, 7 are brackets upon 40 which the arms 6, 6 are mounted for longitudinal and tilting adjustment; 8, 8 are standards mounted for vertical adjustment in the base members 9, 9; and 10 is a draw bar 45 of clay immersed in the glass bath beneath the line of generation of the sheet 4.

All of the foregoing is old except the particular construction of the bowls 5, 5 which is shown in detail in Figs. 2 and 3. These 50 bowls are of cast iron or cast steel and are

provided with the usual slots 11 fitting over the edges of the glass sheet 4. In the drawing operation, the edge of the glass sheet contacts with the bowl at one side of the slot 11 and this contact serves to prevent the sheet from pulling in and narrowing, the manner in which the bowl functions in this particular being well known in the art. On each side of the slot 11, the bowl is cut away in the form of the triangular openings 12, 12. Without these openings in the use of the standard Slingluff edge bowl, the sheet draws thin at the point *a*, as indicated in Fig. 4, this thinning occurring about three or four inches from the extreme edge of the sheet. I have found that by cutting away the bowl, as indicated at 12, 12, this thinning action is avoided and the sheet maintains its full thickness clear to its extreme edge, as indicated in Fig. 2. As a result the breakage involved in drawing the sheet is reduced somewhat and it becomes possible to trim the sheet near to its edge so that a saving of glass is involved. The openings 12, 12 may be made in various forms, but are preferably made in 55 the triangular form shown. The effect of these openings is apparently to reduce somewhat the heating effect of the bowl and cause a thickening of the sheet at the zone *a*. The heating effect of the bowl is due to the fact 60 that it absorbs heat from the body of glass beneath and reflects it back against the bath beneath and against the edge and meniscus of the sheet being drawn.

What I claim is:

1. The combination with apparatus arranged to draw a glass sheet from a pool of molten glass, of means for preventing an inward movement of the edge of the sheet in said pool comprising a shielding bowl of metal above the surface of the pool, but closely adjacent thereto, and having a slot extending inward from its edge and fitting around the edge of the sheet, said bowl having an opening cut through its walls on each side of the slot adjacent thereto.

2. The combination with apparatus arranged to draw a glass sheet from a pool of molten glass, of means for preventing an inward movement of the edge of the sheet in 95 100

said pool comprising a shielding bowl of metal above the surface of the pool, but closely adjacent thereto, and having a slot extending inward from its edge and fitting around the edge of the sheet, said bowl having an opening of triangular shape cut through its wall on each side of the slot adjacent thereto.

In testimony whereof, I have hereunto subscribed my name this 20th day of May, 1930.

R. C. CONN.
